INVENTOR.
Charles A. Christ,

BY Harold E. Miller

ATTORNEYS

UNITED STATES PATENT OFFICE.

CHARLES A. CHRIST, OF LOS ANGELES, CALIFORNIA.

MILK-CAN WASHER.

1,304,260.

Specification of Letters Patent. Patented May 20, 1919.

Application filed October 1, 1918. Serial No. 256,464.

To all whom it may concern:

Be it known that I, CHARLES A. CHRIST, a citizen of the United States, residing at Los Angeles, in the county of Los Angeles and State of California, have invented new and useful Improvements in Milk-Can Washers, of which the following is a specification.

My invention relates to a washing machine for milk cans and the like.

10 It is an object of this invention to provide a washing machine which will wash the interior and exterior of the milk can in one operation while the milk can is held stationary.

15 My invention consists in the construction, combination and arrangement of parts hereinafter described and claimed.

20 In the accompanying drawings, which form a part of this specification, I have illustrated a preferred embodiment of my invention, and in which—

Figure 1 is a vertical longitudinal section taken on line 1—1 of Fig. 2.

Fig. 2 is a vertical section taken on line 2—2 of Fig. 1.

25 Fig. 3 is a rear elevation of my apparatus.

Fig. 4 is a plan view of the can carriage and guide rails.

Fig. 5 is a sectional detail on line 5—5 of Fig. 4.

30 Fig. 6 is a sectional detail of the bumper mechanism on line 6—6 of Fig. 4.

Fig. 7 is a plan of the steam coil used in heating the water in washing.

Fig. 8 is a side elevation of the apparatus 35 showing the cover washing compartment looking in the direction indicated by the arrow in Fig. 1.

40 Referring to the drawings, 10 is a tank, preferably constructed of sheet metal, whose rear portion is provided with a hood 11 having a vapor outlet 12. The top of the front portion of tank 10 is open, the bottom 10' of the front portion of the tank being inclined upwardly toward the front, as clearly shown in Fig. 2. A vertical partition wall 13 divides the tank 10 into a washing compartment 14 and a rinsing compartment 15. The partition 13 is provided with an overflow orifice 16 which will keep the water level

50 constant at that height in the rinsing compartment, and an overflow pipe 17 in the washing compartment 14 located at a trifle lower level than aperture 16 affords an outlet for the washing water. A valved steam coil 18 disposed at the bottom of washing compartment 14 heats the water therein, the

outer end of the steam coil being open and extending through partition 13 into compartment 15.

55 The guide rails, can carriage and revolving paddle mechanism are identical in both compartments, it will therefore be necessary to describe only those in the washing compartment 14 shown in Fig. 2. A pair of tubular guide rails 19 extend from the front of the tank to the rear, said guide rails comprising a downwardly inclined front portion 20 and a rear portion 21. 19' is a bar connecting the free ends of the guide rails 19. 22 are supports for the guide rails spacing them from the bottom of the tank. A can carriage 23 is slidably mounted on the guide rails 19 and comprises a pair of axles 24 having a curvature to conform to the shape of the milk can. The ends of the 70 axles pass through longitudinal slots 25 provided on the adjacent sides of the tubular guide rails 19 and are provided with rollers or wheels 26 which travel in the interior of the tubular guide rails 19. 27 are a pair of 75 crossbars connecting the axles 24. 28 are braces connecting the crossbars 27 to the front axle 24. The front axle 24 has bolted thereon on opposite ends a curved bracket 29 passing over the tubular guides 19 to the 80 outer ends of which a U-shaped carriage operating rod 30 is pivoted. An operating handle 31 is rigidly secured to the middle of the U-shaped rod 30. 32 are a pair of braces connecting the corners of the U-shaped rod 90 30 to the handle 31. A semicircular bail 33 is rigidly secured about midway of the leg portions of the U-shaped rod 30 for holding the can stationary during the washing operation. Each end of the guide rails 19 is provided with a bumper mechanism 34. This bumper consists of a screw cap 35 fitting on the extreme end of the guide rail 19 and having a cylindrical tube 36 secured therein for the reception of a helical compression 95 spring 37, the outer end of which encircles the stem 38 of a plunger 39. The bumpers 34 act as shock absorbers for the can carriage 23.

40 is a bearing mounted on the rear wall 105 of tank 10 in which a shaft 41 is journaled. 42 are pulleys mounted on the shaft 41 for the transmission of power. In axial alignment to the shaft 41 is a paddle 42'. Fast to the shaft 41 are a plurality of arms 43 110 extending at right angles thereto carrying paddles 44, the outer ends of the paddles 44

are connected by a circular brace 45. 46 is a spring hook mounted on the front end of the tank 10 and serves to hold the can carriage 23 on the inclined portion 20 of the 5 guide rails 19. 47 is a can cover washing pocket on the side of compartment 14 communicating with the interior thereof, and having bars 48 dividing the pocket from the washing compartment 14. A similar can 10 rinsing pocket 49 is provided on the side of the rinsing compartment 15. Hooks 50 on the wall of the tank 10 serve to suspend cover supporting rods 51.

In the operation the compartments 14 and 15 are filled with water and a detergent compound is added to the water in washing compartment 14. The water is heated by means of steam coil 18. The can 52 to be washed is placed horizontally upon the 20 can carriage 23 which is held on the inclined portion 20 of the guide rails 19 by means of hook 46. The handle 31 is lowered from the upright position shown in Fig. 1 to the horizontal position shown in Fig. 2, so that 25 the can engaging bail 33 firmly clamps the can in position on the carriage. The hook 46 is released and the carriage slides down to the outer end of the guide rails, the bumpers 34 engaging the front wheels 26 30 of the carriage and acting as shock absorbers as will be understood. The disposition of the guide rails and the paddles is such that the central paddle 42' will enter 35 through the open neck of the can and be disposed along its central longitudinal axis. The outer paddles 44 will surround the can, the carriage 23, and the free end of the 40 guide rail 19, being spaced therefrom a suitable distance.

The agitation produced by the revolving paddles will quickly wash the interior and exterior sides of the milk can. The carriage is then withdrawn and the can is transferred 45 to the rinsing compartment 15 where it is rinsed in hot clear water by a similar operation. The water level, it should be noted, is such that when the can is being washed it does not extend clear up to the upper end 50 of the neck of the can, thus leaving an air space in the can. When the carriage is withdrawn onto the inclined portion 20 of the guide rails 19, the wash water will flow out through the open end of the milk can 53. The object of having the water level below 55 the roof of the mouth of the can 53 when the latter is in position to be washed is to afford free ingress and egress of the water to the can.

The can cover 53 is placed in the washing pocket 47 and washed by the agitation

of the water produced by the revolving paddles. When washed the same is transferred to the rinsing pocket 49.

Various changes in the construction, combination and arrangement of parts may be 65 made by those skilled in the art without departing from the spirit of my invention as claimed.

I claim:

1. A washing machine for milk cans and 70 the like, comprising, a tank, a pair of parallel guide rails consisting of a downwardly inclined front portion and a horizontal rear portion; a can carriage slidably mounted on the guide rails, said carriage comprising 75 a curved can supporting bed and wheels rotatably mounted in said guide rail, a carriage shock absorber means arranged at the end of the horizontal portion of the guide rails, a U-shaped rod pivoted on opposite sides of the can carriage; a semicircular can holding bail rigidly mounted on the U-shaped rod, a handle for operating said U-shaped rod, a plurality of revolving paddles agitating the water within and without the 80 can to be washed, and means for operating 85 said paddles.

2. A washing machine for milk cans and the like, comprising, a tank, a pair of guide rails, a can carriage slidably mounted on the guide rails adapted to support a milk can, manually operated means pivoted to the carriage for clamping the milk can in position, a revolving paddle agitating the water within the can, and a plurality of 90 paddles adapted to revolve in a circular path about the exterior of the milk can and 95 the carriage and guide rails supporting it.

3. A washing machine for milk cans and the like, comprising, a tank, a carriage 100 guide, a carriage movably mounted thereon, means on said carriage for holding a milk can stationary thereon, an agitating member adapted to enter said milk can when the carriage is at the extreme end of the carriage guide, and agitating members about 105 the exterior of the milk can.

4. A washing machine for milk cans and the like, comprising, a tank, a carriage guide, a carriage movably mounted thereon, 110 means on said carriage for holding a milk can stationary, means for agitating the water within and without said milk can when said carriage is in position for the washing operation, and a can cover washing compartment communicating with the tank. 115

In testimony whereof I have signed my name to this specification.

CHARLES A. CHRIST.
